PENCIL SHARPENER

Louis P. Heiman, near Minneapolis, Minn.

Application September 14, 1945, Serial No. 616,199

3 Claims. (Cl. 120—94)

1

This invention relates to a pencil sharpener. Mechanical pencil sharpeners have heretofore been used but said pencil sharpeners are objectionable in operation in certain ways, particularly the sharpeners using a rotating cutting member. With most of the pencil sharpeners of the prior art it has not been possible to secure a real sharp point on the pencil.

It is an object of this invention to provide a simple and efficient pencil sharpener by means of which a pencil can be nicely sharpened with a very fine point.

It is a further object of the invention to provide a simple and efficient structure of pencil sharpener comprising means for holding a pencil and a knife blade disposed in a plane at an acute angle to the longitudinal central axis of the pencil, together with means for effecting a draw cut of said knife blade.

It is more specifically an object of the invention to provide a pencil sharpener having a member with a tapered recess therein adapted to receive a pencil, a knife blade disposed in a plane making an acute angle with the longitudinal central axis of said pencil and disposed at one side of said member and recess together with a rotatable means for giving said knife blade a movement longitudinally of and transversely of said pencil to sharpen the same.

These and other objects and advantages of the invention will be fully set forth in the following description made in connection with the accompanying drawings in which like reference characters refer to similar parts throughout the several views and in which:

Fig. 1 is a view in front elevation of the device;

Fig. 2 is a view in side elevation as seen from the right of Fig. 1;

Fig. 3 is a top plan view; and

Fig. 4 is a horizontal section taken on line 4—4 of Fig. 1, as indicated by the arrows.

Referring to the drawings, a pencil sharpening device is shown comprising a frame having a supporting member 10. While this member might be variously formed, in the embodiment of the invention illustrated it is shown as a flat plate having its lower portion 10a offset from its main portion, said offset portion being connected to the main portion by a downwardly or angularly extending portion 10b. Plate 10 in its upper portion is provided with a circular opening 10c. A bar 11 extends transversely of plate 10 at its upper portion, said bar being spaced some distance from plate 10 and secured thereto by headed screws 12 which extend through plate 10 and through spac-

2

ing blocks 13, said screws being threaded into bar 11. A gear 14 is provided and while this might be variously formed, in the embodiment of the invention illustrated it is shown as a spur gear, the same being journaled on a headed stud 15 secured in bar 11. A handle 17 is secured to gear 14, the same projecting through opening 10c and being secured to gear 14 by a headed screw 18 which extends through gear 14 and is threaded into handle 17. Gear 14 meshes with a pinion 20 journaled on a stud 21 secured in plate 10, and pinion 20 has a crank pin 22 projecting from one side thereof. A pitman 23 has an aperture at one end through which crank pin 22 extends so that the same is pivoted on said crank pin. Crank pin 22 is headed and extends through the aperture in member 23, as stated, and is threaded into gear 20. The other end of pitman 23 is pivotally connected by a pivot stud 24 to the lower end of a bar 25, which in turn is pivotally connected by the pivot stud 26 to bar 11. The bar or pitman 23 forms a blade or knife-carrying member and has secured thereto in any suitable manner a knife blade 28. A member or block 29 is provided secured by spaced headed screws 30 to the lower portion 10a of plate 10. Member 29 has a tapered recess 29a therein, as shown in Fig. 4, said recess being open somewhat at the outer side of block 29. Blade 28 is disposed along one side of block 29, as shown in Fig. 4, and it will be seen that said blade 28 is at an acute angle to the longitudinal central axis of the tapered recess 29a and of a pencil P disposed therein. As illustrated, recess 29a has a small transverse dimension at its smaller end at one end of block 29. A resilient plate or spring 32 is secured by a headed screw 33 to one side of block 29 and bears at its upper end against one side of blade 28, the same acting to hold said blade against member 29 and pencil P.

In operation the pencil P will be placed in the recess 29a. It will thus engage the rear side of said recess and will also engage the inner side of blade 28. The operator now rotates gear 14 by means of the handle 17 in a counter-clockwise direction, as seen in Fig. 1 and this in turn rotates pinion 20 and crank pin 22. Member 23 is oscillated by crank pin 22, said member 23 swinging at one end with the lower end of bar 25, which 45 swings about pivot 26. Member 23 and knife blade 28 are thus given a movement longitudinally of pencil P and transversely thereof. Knife 28 thus moves along pencil P and transversely thereof. Knife 28 thus moves along pencil P and effects 50 a draw cut thereon. The pencil P will be inter-

mittently rotated and pushed or advanced in recess 29a until a very fine point is formed thereon, as illustrated in Fig. 4. The blade 28 will of course be quite sharp and the wood of the pencil is nicely and progressively shaved off so that the sharpened end of the pencil gives a neat and pleasing appearance. A smoother cut can more consistently be made than with a rotating tool which at times must rotate against the grain of the wood.

From the above description it will be seen that I have provided a pencil sharpener of quite simple construction and yet one which is very efficient. The sharpening operation can be very rapidly performed and a very fine point can be produced on the pencil lead. The plate 10 can readily be provided with attaching means so that it can be attached to a wall, desk or other desirable object. The device has been amply demonstrated in actual practice and found to be very successful and efficient.

Applicant's device is so constructed that a used razor blade can very conveniently be used for the blade 28. Such razor blades when not desirably sharp for shaving are still very efficient as pencil sharpening blades. The blades in applicant's device can therefore be provided at practically no expense. Such razor blades are thin and function very effectively in applicant's device.

It will, of course, be understood that various changes may be made in the form, details, arrangement and proportions of the parts, without departing from the scope of applicant's invention, which generally stated, consists in a device capable of carrying out the objects above set forth, in the parts and combinations of parts disclosed and defined in the appended claims.

What is claimed is:

1. A pencil sharpener having in combination, a vertically extending frame, a gear journaled in said frame, a handle for turning said gear, a pinion at one lower side of said gear meshing therewith, a pitman pin secured to said pinion and spaced from the axis of said pinion, a link mounted at one end on said pin, an upwardly extending link swingingly secured at its upper end to said frame, the other ends of said links being pivoted together, a blade secured to and in substantially parallel relation to said first mentioned link, a member secured to said frame below said gear and pinion having a socket therein, the axis of which is at an angle to the plane of said blade, said socket having a conical end portion open at one side, along which side said blade moves with a downward and longitudinal movement.

2. A pencil sharpener having in combination, a plate arranged in a substantially vertical plane, a gear journaled on said plate, a pinion at one lower side of said gear journaled in said plate and meshing with said gear, a pitman pin secured to said pinion, a link having one end pivoted on said pin, an upwardly extending link swingingly carried by said plate at its upper end, said links having their other ends pivotally connected, a blade secured to and extending longitudinally of said first mentioned link having an edge at its lower side, said plate being offset at its lower portion, a block secured to the offset portion of said plate having a recess therein with a conical end, said recess being open at one side of said block and said blade moving along said side of said block.

3. A pencil sharpener having in combination, a plate disposed in a substantially vertical plane, a bar extending across said blade and secured at its ends to said plate and being spaced from said plate, a stud extending through and between said plate and bar, a gear journaled on said stud, a handle secured to said gear, said plate having an opening therethrough accommodating rotation of said handle with said gear, a pinion journaled on said plate at one lower side of said gear and meshing with said gear, a pitman pin secured to said pinion, a link journaled at one end on said pin and extending across said plate, an upwardly extending link swingingly mounted at its upper end to said bar, the other ends of said links being pivotally connected, a blade secured to said first mentioned link extending therebelow and having an edge at its lower side, said plate having an offset portion adjacent its bottom offset away from said gear, a block secured to said offset portion and having a recess therein having a conical end portion, said end portion being open at one side of said block and said blade moving along said side and said recess.
